WALL GUNRACK

Harry E. Monroe, Los Angeles, Calif.

Application March 7, 1952, Serial No. 18,814

Term of patent 14 years

(Cl. D33—3)

To all whom it may concern:

Be it known that I, Harry E. Monroe, a citizen of the United States, residing at Los Angeles, in the county of Los Angeles and State of California, have invented a new, original, and ornamental Design for a Wall Gun Rack, of which the following is a specification, reference being had to the accompanying drawing, forming a part thereof.

Figure 1 is a front elevational view of a wall gun rack, showing my new design;

Fig. 2 is a side elevational view thereof looking from the left to the right of Fig. 1;

Fig. 3 is a side elevational view thereof looking from the right to the left of Fig. 1.

Fig. 4 is a rear view thereof on a reduced scale.

I claim:

The ornamental design for a wall gun rack, as shown.

HARRY E. MONROE.
